HARRY DEFOREST MADDEN, OF NEWARK, AND JOHN JOSEPH HIGGINS, OF EAST ORANGE, NEW JERSEY, ASSIGNEES TO WESTINGHOUSE LAMP COMPANY, A CORPORATION OF PENNSYLVANIA.

MANUFACTURE OF INCANDESCENT LAMPS.

Application filed March 25, 1922. Serial No. 546,642.

This invention relates to incandescent lamps and their manufacture and more particularly to mounts for tipped or tipless lamps.

5 An object of our invention is the provision of a method for the manufacture of incandescent lamps whereby the operations to be performed may be made more nearly automatic, thereby increasing production and 10 cheapening the cost thereof.

Another object of our invention is the formation of a mount in which the leading-in wires are utilized to accomplish the function of an arbor, as at present employed in 15 standard lamp practice.

A further object of our invention is the provision of a mount of few parts, constructed to withstand rough handling and to be more resilient because of the utilization 20 of more flexible parts.

The ordinary mount, as at present constructed, comprises a flare, an exhaust tube, if designed for a tipless lamp, leading-in wires sealed therebetween and a glass arbor 25 extending from the press or, if of pressless construction, from the junction between the flare, exhaust tube and leading-in wires. The filament is supported from the arbor on the usual metallic hooks. The use of an 30 arbor entails the disadvantages of having an additional piece of glass to handle, of usually requiring a machine to place buttons thereon and of one to insert the usual wire hooks therein. When a mount is made 35 with the usual glass arbor provided with wire hook supports, the leading-in wires are connected directly to the ends of the filament and that is all the support they give thereto.

40 By our invention the glass arbor is dispensed with and the leading-in wires extended beyond the press for a distance approximately corresponding to the length of a glass arbor. Suitable holding means, such as coils or crimpings, are provided at points 45 on the leading-in wires corresponding to the location of the usual buttons, and plates or

discs, preferably of a refractory insulating material, such as mica, provided with individual filament supports, such as notches, 50 cleats, or projections, are supported by the coils. A filament, or the like, is wound around the individual supports connecting the ends of the leading-in wire extensions.

According to the present invention, we 55 have obviated the objection inherent in a glass arbor, by substituting therefor, leading-wire extensions, which, being metallic, are not subject to breakage like glass arbors. Then, the usual metallic hooks for supporting the filament are replaced by less delicate 60 and more easily handled plates or discs of mica or other suitable refractory insulating material. By means of these improvements, 65 production is facilitated and many operations now being performed in semi-automatic machines may be made fully automatic. These operations comprise, lead forming, inserting discs in same and winding filament. The holding coils are formed 70 close enough to firmly clamp the mica plates between their elements so that, when the leading-in wires and plates with the filament wound thereon are assembled, they may be handled as a unit, even before consolidation 75 with the flare. This makes possible the winding of the filament before the lead-in wires are fused in the flare, an operation heretofore impossible. Automatic winding is made practicable by the elimination of 80 the very easily bent metallic hooks for filament supports, heretofore used.

Additional advantages comprise the elimination of arbor-making machines, no arbor being required, and the doing away with inserting machines, as no wire hook supports are used. The mica plates act as baffles to 85 prevent overheating of the bulb if used in a gas-filled lamp.

Other objects and advantages of the invention will be apparent as the description proceeds. Preferred embodiments of the invention are illustrated in the accompanying drawing, in which,

- Fig. 1 is an end view of a mount for an incandescent electric lamp embodying my invention;
- Fig. 2 is a side elevation thereof;
- Fig. 3 is a section on the line III—III of Fig. 2, on a larger scale, looking in the direction of the arrows;
- Fig. 4 is a partial side elevation showing a modification;
- Fig. 5 is a side elevation of the complete lamp; and
- Fig. 6 shows a modified form of filament-supporting disc.
- The invention, as illustrated, is applied to a mount for a tipless lamp. It would be appropriately represented for a tipped lamp by merely omitting the contraction or exhaust tube and the small hole in the flare near the connection between the flare and the leading-in wires.
- Referring to Figs. 1 to 3 inclusive, the flare 1 is shown combined with an exhaust tube 2. The usual hole from the exhaust tube, through the flare, is represented by 3.
- Leading-in wires 4, preferably of dumet, which is a standard form of wire for such purpose, preferably formed as a core of nickel-steel surrounded by a sheath of copper, are shown extending to the stem press 5 from below the flange of the flare. The dumet wires 4 may be extended beyond the press 5 if made sufficiently strong, but it is considered preferable to make such extensions 6 of stiffer wire composed of nickel or other metal not containing occluded gases. Preferably, two complete coils or helices 7 are formed in each of the nickel extensions of the leading-in wires 6, between which the bottom filament support, preferably comprising a plate or disc 8 of mica or other refractory insulating material, is held.
- The nickel leads are further extended and formed with similar helices 9, between which the top filament support 11 extends. This support is constructed of a material similar to that of the disc 8 but is shaped slightly different, as will be noted by comparison of Figs. 1 and 3.
- The nickel leads 6 are extended, preferably at right angles to their main portions and parallel to each other from the last or topmost coil, and connected to the filament 12 at 13. See Fig. 1.
- Referring particularly to Figs. 1 and 3, it will be seen that the lower disc 8 is provided with individual filament supports 14, preferably in the form of outstanding or radial cleats. The individual supports 15 on the upper disc 11 are similarly formed but spaced midway between the angular positions of the individual supports 14, corresponding to the usual arrangement when metallic hooks are employed. One less cleat is employed on support 11 than on support 16 for the reason that the ends of the nickel leads, shown connected to the filament, take the place of one cleat 15.
- The filament is wound on the spider thus formed from its connection with one of the nickel leads at 13 around the nearest cleat 14 up and over the nearest cleat 15 and the operation is continued until all the cleats are each supporting a portion of the filament. The free end of the filament is then connected, at 13, to the other nickel lead.
- The mica supports 8 and 11 are each provided with spaced apertures 16 and 17, with the nickel leads extending therethrough. The coils 7 and 9 hold the discs in place. Instead of two apertures in each disc, one elongated aperture 21 through which both leads extend, may be employed, within the scope of the present invention. See Fig. 6. Any other suitable means may be employed for holding the mica discs in position on the nickel leads.
- In making a mount embodying the present invention, the flare, the contraction tube, if used, and the leading-in wires are placed in a stem-making machine and, after applying heat, are consolidated in a well known manner. Wires of the same formation throughout or compound wires comprising dumet leads with heavier nickel extensions, such as illustrated in the drawing, may be used. The extensions are then bent to provide the coils for holding the mica which are then put in position. The ends of the leading-in wires are turned at right angles, as shown, and trimmed to length, if necessary, thereby completing the spider. The filament is connected and wound on this spider as heretofore described, thus forming a complete mount.
- Fig. 4 is a partial side elevation of a mount constructed similarly to that shown in Figs. 1 to 3, inclusive, except that the flare 1 and the exhaust tube 2 are consolidated with the leading-in wires 4 by a method described and claimed in a copending application of J. J. Higgins, Serial No. 546,679, filed March 25, 1922, and assigned to the Westinghouse Lamp Company.
- This method consists essentially in uniting the flare, the exhaust tube, if used, and the leading-in wires by the external application of heat and the internal application of air pressure, thereby causing consolidation of the parts by the surface tension of the glass, when in a softened state assisted by the pressure of the gas fires, if such are used, acting against the air pressure on the inside of the exhaust tube. In this modification, there is no press, as generally understood, and no hole 3, as in Fig. 2. The press is replaced by a junction between the parts formed entirely by fluid means. The mount formed is distinctive in that this junction is oval or circular in section instead of being flat or elongated, as when formed by mechanical

pressing. The air is exhausted through the tube 2, which, in this instance, is shown of small section and, therefore, without the usual contraction for tipping off. The hole

5 3 is replaced by the open inner end 18 of the exhaust tube. Except for these variations, this modification may be identical with that illustrated in Figs. 1 to 3, inclusive, or may have leading-in wires consisting entirely of dumet or other suitable wire.

10 Fig. 5 shows the complete lamp formed with a mount constructed according to our invention. After forming the mount as heretofore described, the same is sealed in the bulb 19 by any well known means. The bulb is then exhausted or the air therein replaced by an inert gas, by means of the exhaust tube 2. After sealing off, a base 20 is applied in any suitable manner.

15 20 By means of the present invention, the incandescent filament is supported by refractory insulating plates or discs, which, being poorer heat conductors than the usual wire hook supports, will not dissipate the heat of the filament as rapidly from the points of contact therewith. A mount is provided according to this invention which is cheaper to manufacture, more rugged in construction and composed of fewer parts than the standard types now on the market. In a gas-filled lamp, the mica plates act as baffles to prevent undue heating of the bulb and base.

25 30 While we have illustrated what we now consider to be the preferred embodiment of our invention, it is to be understood that many changes may be effected therein and that our invention is to be limited only by the scope of the appended claims.

35 What is claimed is:

40 1. The method of making spiders for incandescent lamps comprising the fusing of leading-in wires in a flare, shaping said wires and supporting mica discs on the shaped portions of said wires.

45 2. The method of making spiders for electric lamps comprising sealing leading-in wires in a flare, coiling the wires and supporting refractory insulating plates thereon.

50 3. The method of making mounts for incandescent lamps comprising the fusing of leading-in wires in a flare, shaping said wires to form supporting means, supporting mica discs having extensions thereon and winding a filament on said extensions of the discs.

55 4. The method of making mounts comprising the insertion of lengthened leading-in wires in a flare, coiling the same to form supporting means, attaching a refractory insulating support and winding a filament from the end of one wire around the support to the end of the other wire.

60 5. The method of constructing mounts for electric lamps comprising sealing leading-in

wires in a flare, bending the wires, supporting mica discs at the bends and attaching a filament thereto.

6. The method of making incandescent lamps comprising providing leading-in 70 wires with supporting elements, attaching refractory insulating plates thereto by means of said elements, winding a filament on elements of the plates and consolidating the leading-in wires in a flare to form a mount. 75

7. The method of making incandescent lamps comprising shaping extended leading-in wires to provide them with clamping elements, supporting suitable plates between the wires by said elements, winding a filament on said plates and consolidating the structure so formed with a flare to form a mount. 80

8. A filament support for incandescent lamps comprising perforated mica discs 85 with integral outstanding projections and a pair of leading-in conductors disposed in spaced relation and passing through said discs, and means associated with said leading-in conductors for holding said discs in 90 given positions for the disposition of a filament upon the outstanding projections.

9. An article of manufacture comprising a plate of refractory insulating material with integral outstanding holding elements, 95 a pair of leading-in wires spaced apart by a portion of said plate and secured thereto to hold the plate for the disposition of a filament on said projections.

10. An arborless spider comprising a 100 flare and extended leading-in wires supporting thereon refractory insulating plates formed with integral means adapted to directly support a filament.

11. An arborless spider comprising a 105 flare and extended leading-in wires coiled and mica plates supported at the coils.

12. A spider for incandescent lamps comprising a flare, leading-in wires comprising dumet with nickel extensions embedded in 110 said flare, said extensions being formed with supporting means and mica plates supported thereon.

13. A filament mount comprising a flare, leading-in wires sealed therein and supporting a plurality of refractory discs disposed in parallel planes having individual holding means thereon and an incandescent filament supported directly by said means. 115

14. An arborless mount comprising a flare, 120 extended leading-in wires bent to form supports, mica plates supported thereon and provided with individual filament-holding elements and a filament supported by elements of the mica plates.

15. A mount for incandescent lamps comprising a flare, leading-in wires comprising dumet with nickel extensions being formed with supporting means and refractory insulating plates having filament cleats sup- 130

ported thereon and a filament wound so as to be supported on the cleats.

16. An incandescent electric lamp comprising a bulb, a base, a mount within said bulb comprising leading-in wires extending longitudinally of the axis of the bulb, insulating plates attached to said wires and disposed transverse to the said axis of the

bulb to serve as baffles and means at the perimeter of said plates to receive a filament.

In testimony whereof, we have hereunto subscribed our names this 24th day of March 1922.

HARRY DeFOREST MADDEN.
JOHN JOSEPH HIGGINS.
